UNITED STATES PATENT OFFICE.

HENRY JOINSON, OF ARLINGTON, NEW JERSEY.

DESIGN FOR AN INTERLOCKING PLATE FOR SIGNAL-STANDS.

SPECIFICATION forming part of Design No. 29,502, dated October 18, 1898.

Application filed September 15, 1898. Serial No. 691,047. Term of patent 14 years.

To all whom it may concern:

Be it known that I, HENRY JOHNSON, a citizen of the United States, and a resident of Arlington, in the county of Hudson and State 5 of New Jersey, have invented and produced a new and original Design for an Interlocking Plate for Signal-Stands, of which the following is a specification, reference being had to the accompanying drawings, forming a part 10 thereof.

The leading features of my design consist in an interlocking plate for signal-stands presenting in side elevation a series of vertical and horizontal bars crossing one another at 15 right angles, portions of the horizontal bars being offset from the plane of the vertical bars.

In the accompanying drawings, Figure 1 is

a view of the plate in side elevation. Fig. 2 is an end view, and Fig. 3 is a top plan view. 20 A represents the vertical bars.

B represents the horizontal bars, and C represents portions of the horizontal bars which are offset from the plane of the vertical bars. 25

What I claim is—

The design for an interlocking plate for signal-stands, substantially as shown and described.

In testimony that I claim the foregoing as my invention I have signed my name, in presence of two witnesses, this 16th day of April, 1898.

HENRY JOINSON.
